(57) **CLAIM**

The ornamental design for a drum lid for a gutter vacuum, as shown and described.

DESCRIPTION

FIG. 1 is a top, rear perspective view of a drum lid for a gutter vacuum showing my new design;

FIG. 2 is a side view thereof;

FIG. 3 is a top view thereof;

FIG. 4 is a top, rear perspective view of the middle portion of a drum lid for a gutter vacuum;

FIG. 5 is a side view of FIG. 4;

FIG. 6 is a top view of FIG. 4;

FIG. 7 is a top view of the bottom portion of a drum lid for a gutter vacuum;

FIG. 8 is a side view of FIG. 7;

FIG. 9 is a top, rear perspective view of FIG. 7;

FIG. 10 is a side view opposite FIG. 8;

FIG. 11 is a top, rear perspective view of the tube portion of a drum lid for a gutter vacuum;

FIG. 12 is a side view of FIG. 11;

FIG. 13 is a top view of FIG. 11; and,

FIG. 14 is a top, front perspective view of a drum lid in assembled condition.

FIGS. 4-12 are shown separate for clarity of illustration. The design is shown fully assembled in FIGS. 1-3 and 14.
